PORTABLE RECEPTACLE

Robert Herrmann, New York, N. Y., assignor to
 Heinrich, Herrmann & Weiss, New York, N. Y., a
 copartnership composed of Adolph Weiss and
 Robert Herrmann

Application March 1, 1934, Serial No. 713,457

3 Claims. (Cl. 150—42)

This invention relates to portable receptacles, and has among its objects the provision of a device of the character described having improved means whereby the receptacle can be fully opened for the orderly reception or convenient placement therein of various kinds of articles.

Another object of the invention is to provide a device of the nature set forth having a slide fastener and improved means associated therewith to facilitate the use of the slide fastener both in connected and disconnected conditions, and to render the action of the device positive, or automatic, or both.

Another object of the invention is to furnish a device of the class specified having improved means for use with a slide fastener whether the same be of the permanently connected kind or of the type wherein the slide element is detachable from a portion of the fastener.

20 A further object of the invention is the provision of a device of the character alluded to having relatively few and simple parts, and which is inexpensive to manufacture, convenient and reliable in operation, neat in appearance, and durable and efficient in use by the ordinary unmechanical person.

Other objects and advantages of the invention will become apparent as the specification proceeds.

30 With the aforesaid objects in view, the invention consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a perspective view of a device embodying the invention.

Fig. 2 is an end view in fully open position thereof, the slide being in detached position.

Fig. 3 is an enlarged vertical sectional view taken on line 3—3 of Fig. 1.

45 Fig. 4 is an enlarged fragmentary view in end elevation of the device, the slide fastener being open but the slide being in connected condition.

Fig. 5 is a fragmentary perspective view of the device as shown in Fig. 4, but with the receptacle walls swung open.

Fig. 6 is a view corresponding to Fig. 5, but with the slide detached, so that the receptacle can be fully expanded.

Fig. 7 is an enlarged fragmentary view in end elevation showing a modified means for control-

ling the detachment of the slide, the fastener being open and the slide fully attached.

Fig. 8 is a similar view of the same with the controlling means detached, and showing initial release of the slide.

Fig. 9 is a similar view of the same and showing the automatic disconnection of the slide coincident with the full outward swinging of the receptacle walls.

Fig. 10 is a fragmentary view with parts in perspective showing the disconnected slide fastener and structural details of the latter.

Fig. 11 is an enlarged sectional view taken on the line 11—11 of Fig. 10.

Fig. 12 is a fragmentary view in end elevation of a further modification of the invention in closed position.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Referring in detail to the drawings, 15 denotes a device such as a portable receptacle embodying the invention. The receptacle may have for illustrative purposes, a pair of substantially parallel side walls 16, 17. The receptacle may be horizontally elongated, and its lower portion may have a longitudinal partition 18, interconnected with the side walls by continuous bottom and end gussets 19, 20 respectively. In this manner, compartments 21, 22 are provided, the latter being normally contracted and the former normally expanded and provided with sub-compartments, 90 not shown, for various different articles. The upper portion of the receptacle may have continuous flexible marginal portions or flaps such as 23, 24 for the respective walls 16, 17, and extending along top and end edges of said walls. 95 Releasably interconnecting said marginal portions is a conventional slide fastener 25, whereby a continuous, uniform closure wall is provided for the receptacle.

Desirably the side walls 16, 17 of the receptacle 105 are adapted to be collapsed as by having longitudinal hinge lines as at 26 parallel to the upper and lower edges of the receptacle. The said hinge lines may be substantially in alignment 110 with the meeting portions of the gussets 19, 20

and the marginal portions 23, 24 at the ends of the receptacle. A suitable construction for each wall 16, 17 consists in utilizing two sheets of sheet reenforcement or stiff paper board 27, 28, 5 longitudinally spaced from each other along the region 26. These reenforcements may be externally covered by a single sheet of pliable fabric, such as cloth or leather 29, and internally covered by a similar pliable sheet of material 30. The latter may only partially cover the reenforcement 28. Continuous lines of stitching 31 may interconnect the gussets 19, 20 with the reenforcements 22 and the external covering 29, the latter being secured in infolded relation about the adjacent edges of the gussets and reenforcements. The continuous lines of stitching 31 may also interconnect the reenforcements 27 with the linings 30 and the coverings 29, the latter being likewise secured in infolded relation over the former. Horizontal lines of stitching at 33 may interconnect the linings 30 with the reenforcements 28. The several parts of the wall structure may also be adhesively interengaged as required. The external coverings may provide end lips continuously stitched at 34 to the marginal flaps 23, 24 respectively. The gussets 19, 20 may be of one piece of material, and continuously stitched to the partition 18 as at 35. It will be understood that the line of stitching 35 20 will extend throughout the gussets at the bottom and ends of the receptacle, the lines of stitching 31 being substantially continuous along the top, bottom and ends of the receptacle, and the lines of stitching 34 extending along the top and ends 35 of the receptacle coextensive with the marginal portions 23, 24.

To facilitate the swinging open of the flap portions F, F' of the walls 16, 17, about the hinge lines 26, as shown in Figs. 2 and 5, the flexible marginal portions 23, 24 may each have identical pliable tongues 36, 37, respectively which are continuous with said portions and project downward therefrom from points as at 39 determined by the hinge lines 26. The tongues or tabs 36, 37 40 externally overlie the adjacent portions of the gussets 19, 20 and normally fall between the side walls 16, 17 as shown in Fig. 1. The opposite ends of the flexible marginal portions may terminate as at 39 in Fig. 3, slightly below the upper 45 edge of the adjacent upright gussets.

The slide fastener 25 may include the usual series of interlocking hooks 40 secured to fabric stripping 41 and continuously stitched as at 42 to the flexible marginal portions 23, 24 from 50 end to end thereof, including the tabs 36, 37. The latter may consist of material underfolded upon itself at the lower edges of the tabs to afford a strong multiply structure as shown in Fig. 11, and hereinafter described in detail.

While the slide fastener may be of the permanently interconnected type, I preferably employ one in which the slide is in part detachable. For example, the fastener 25 may include 55 conventional fastener details including a slide 43, a finger piece 44 therefor and releasably interengageable guide elements 45, 46, as shown particularly in Fig. 10. These elements may have similar anchor portions 47 in the nature of strips 60 of sheet metal which extend transversely into the ends of the tabs 36, 37. Specifically, the tab material has an underfolded portion 48 enclosing the anchorage and connected in place by stitching 49. To these tabs the anchorages are 65 individually secured as by rivets or eyelets pass-

ing through the tabs and suitable holes in the anchor strips 47.

The element 45 is provided with a tubular portion 51, longitudinally open at 52; and having a stop projection 53 below the tubular portion and in line therewith. The element 46 includes an elongated substantially tubular or hollow pin 54 aligned with the respective series of hooks 40, and adapted for removable insertion into the guideway 55 of the slide and being of sufficient length to extend into the guide 51 with the lower end of the pin in abutment with the stop 53. When so assembled, as shown in Figs. 4 and 5, the slide fastener 25 can be closed in the usual manner, by merely drawing the slide 43 along the fastener to the ends 39, at which further movement of the slide is suitably stopped, the receptacle being then completely closed.

When the slide fastener 25 is opened, by moving the slide 43 into abutment with the guide portion 51, which is as far as the slide will travel, the fastener is not only open, but the pin 54 may be readily pulled out from engagement with the slide and the element 45 so as to disconnect the slide from one side of the fastener, as shown in Fig. 6. This removal of the pin is readily accomplished by a pull on the flexible tab 37, and the receptacle can now be fully expanded, and the compartment 22 opened up to receive articles as desired.

When the receptacle 15 has been packed, it may be closed by grasping the flexible tab 37 for reinserting the pin 46, whereupon the slide 43 can be pulled to close the fastener.

A limited degree of expansibility in the compartments of the receptacle is provided by the tabs 36, 37 themselves. Thus when the slide fastener is opened, although the slide is not detached, nevertheless on swinging the flaps F, F', to open position, the flexible tabs yield and generally spring outward as shown in Fig. 5, due to the tension exerted thereon by the continuous marginal portions 23, 24 which are pulled outwardly by the flaps F, F'.

It will be noted that when the receptacle 15 is opened as in Fig. 5, the pin 54 tends to frictionally remain in engagement with the slide and the element 45, due to the lateral pull exerted on the pin. Hence there is the advantage that the slide is not detached, and the necessity for reconnecting the same is avoided. At the same time, due to the outward flexing of the tabs 37, sufficient latitude is afforded for a fair degree of opening up of the receptacle 15 for accessibility to the compartments thereof.

In Figs. 7 to 9 is shown a modification of the invention, embodied in a device such as a portable receptacle 57, of the type adapted to be carried under the arm. The receptacle 57 and its slide fastener 25 may be exactly the same in construction as the receptacle 15, with the exceptions that will now be described. These exceptions will be best understood by brief reference to the objects to be attained by this modification. It is intended, first, to effect a release of the pin 54 directly upon laterally swinging the flap F', so as to avoid the necessity of pulling the pin out of engagement by manually grasping a tab or associated part; and, second, to provide a convenient means for maintaining the pin 54 fully engaged to permit manipulation of the slide without a binding due to improper interpositioning of the slide fastener hooks. Coincidentally with, or independently of the second object, it is desired to afford a reliable and particularly simple means

for controlling the disconnection of the slide 43. I have found that the first of these objects can be accomplished by such a coordination of the mounting elements for the slide fastener that the lateral pull at the pin 54, indicated in Fig. 5, becomes generally axial as shown in Fig. 8. This result I accomplish by continuous attachment of the tab 36a to a fixed part, such as the wall 16. For instance, the line of stitching 31 may be carried continuously along the outer edge of the tab 36a, and the latter additionally tacked as at 58 to the adjacent edge of the wall 16. If now the flaps F and F' are swung open, the tab 37 is raised more than the tab 36a, so that the pin 54 is pulled upward and released to detach the slide 43.

Control of the release and reconnection of the slide 43 may be effected by means controlling the relative movement of the tabs 36a and 37, preferably independently of the flaps F, F', and in any case despite the tendency of the latter to influence this action. I have found a simple expedient for effecting these results by providing the tab 37 with releasable anchorage or extension such as a strap 59, that may be suitably connected as at 60 to the tab 37 at the back thereof, and extends downward therefrom to be detachably connected to a relatively fixed part, such as the partition wall 18, externally of the receptacle. The connection may be of the snap fastener type 61, including head and socket elements 62, 63 respectively, for the strap and partition, the latter having its fastener element riveted or otherwise secured thereto through the adjacent gusset material in a manner that will be readily understood. If desired, the strap 59 may be inelastic, but elastic webbing material is preferable.

In use, the element 59, in the attached position of Fig. 7, exerts a constant downward tension on the tab 37 so as to maintain the pin 54 fully seated in the socket 51. Otherwise, an upward pull on slide 43 tends to elevate the pin 54 so that the slide fastener hooks cannot interfit, thus causing the slide to bind. This is extremely annoying particularly to an unmechanical person. While the pin 54 may be locked in the socket 51, the necessary means would require manipulation of objectionably small mechanical parts, inconvenient and difficult to observe and to handle. The element 59 being attached, any accidental disconnection of the slide is prevented. Moreover, the elasticity of the element 59 will permit a degree of upward movement of the tab 37 on outward swinging of the wall flaps, to afford flexibility in the action of the receptacle; and even if the pin 54 is withdrawn to some extent from its socket 51, the swinging back to vertical of the wall flaps will cause automatic resetting of the slide fastener elements by the strap 59.

If the strap 59 is disconnected at 61, the pin 54 is readily detached as hereinbefore described. Reconnection may be quickly effected by inserting the pin 54 through the guide 55 of the slide into the socket 51 and securing the strap 59 at 61. The slide fastener can then be manipulated again in the usual manner.

In Fig. 12 is shown a further modification 65 of the invention which is similar in principle to the device 57, and is precisely the same in construction therewith, except that the element 59 is replaced by laterally overlapping identical flaps 66, 67 on the tabs 36b, 37b disposed below the slide fastener and interconnected by the conventional releasable snap fastener 68. It is noted

that one element of the latter is in close proximity to the anchorage 47 or the stop 53 or other suitable fixed rigid part, or in substantial contact therewith so as to maintain the tabs 36b, 37b in accurate relation to accomplish substantially the objects of the device 57. If desired, the snap fastener element that is secured to the tab 36b may also be connected to said anchorage, while the other element and its flaplet 66 is preferably freely movable for connection and release of the snap fastener. A portion of the socket 51 and its stop 53 may be disposed within the flaplet 67, the plies of which may be open sufficiently to permit the entrance of the pin 54 into the socket as hereinbefore mentioned.

By virtue of the aligned relation of the snap fastener 68 with the slide fastener, any stress exerted on the former is uniformly taken up, without distortion of the pliable structure of the device. The features 65 to 68, as well as 59 and 61 can be incorporated as desired in the device 15.

It will be appreciated that various changes and modifications may be made in the device as shown in the drawings, and that the same is submitted in an illustrative and not in a limiting sense, 100 in the scope of the invention being defined in the following claims.

I claim:

1. A portable receptacle having walls swingable apart from each other, the receptacle having a relatively fixed portion and a complementary movable portion connected to one of the said walls for movement thereby, a slide fastener continuously interconnecting said walls and said portions, said slide fastener having longitudinally disconnectible portions and said walls being adapted to cause said disconnection on swinging movement away from each other, and means releasably connecting the said movable portion with a relatively fixed part of the receptacle to prevent disconnection of the slide fastener portions. 105

2. A portable receptacle having a relatively fixed portion and including walls having a slide fastener, the latter including end portions longitudinally relatively movable for detachment of the slide from one of said portions, one of said walls being swingable, one of said slide fastener portions being connected to the swingable wall for detaching movement thereby, the other corresponding part of the slide fastener being connected to said relatively fixed portion, whereby on swinging said swingable wall away from the other wall, the slide fastener portions are adapted for automatic disconnection, as set forth. 120

3. A portable receptacle having a pair of substantially parallel side walls at least one of which has a hinge line intermediate of the top and bottom thereof, said side walls being otherwise relatively stiff throughout, a gusset continuously interconnecting the side walls along the bottom 135 and ends thereof substantially up to the horizontal plane of the hinge line, flexible marginal strips individually connected to said walls continuously along the tops and end thereof substantially down to the plane of the hinge line, 140 said flexible marginal strips having end portions at one end of the receptacle projecting downward below the plane of the hinge line and at least one of said end projecting portions being movable relatively to the side walls, and a slide fastener continuously interconnecting said flexible marginal strips, including said end projecting portions centrally therebetween, the width of said marginal strips and slide fastener being approximately equal to that of said gusset in 150

substantially expanded condition of the latter, said slide fastener including a slide and end portions movable relatively to each other for detachment of the slide from one of the end portions of the slide fastener, and the end portions of the slide fastener being located at and secured to the corresponding projecting end por-

tions of the flexible marginal strips, whereby the hinged wall can be opened and the movable end projecting portion of a marginal strip moved to facilitate interconnection of the said end portions of the slide fastener, as set forth.

ROBERT HERRMANN.
